CLAIM

The ornamental design for a textile machine, as shown and described.

DESCRIPTION

FIG. 1 is a perspective view of a textile machine;

FIG. 2 is a top plan view thereof;

FIG. 3 is a bottom plan view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is an enlarged top plan view of a portion of FIG. 2;

FIG. 9 is an enlarged bottom plan view of a portion of FIG. 3;

FIG. 10 is an enlarged front elevational view of a portion of FIG. 4;

FIG. 11 is an enlarged rear elevational view of a portion of FIG. 5;

FIG. 12 is an enlarged left-side elevational view of a portion of FIG. 6; and,

FIG. 13 is an enlarged right-side elevational view of a portion of FIG. 7.

The dot-dash broken lines in the drawings illustrate partial view indicia that forms no part of the claimed design. The dash-dash broken lines in the drawings depict portions of the textile machine that form no part of the claimed design.
